UNITED STATES PATENT OFFICE.

HENRY J. RUPP, OF QUINCY, ILLINOIS, ASSIGNOR TO GEM CITY STOVE MANUFACTURING COMPANY, OF QUINCY, ILLINOIS, A CORPORATION OF ILLINOIS.

DESIGN FOR A STOVE CASING OR SIMILAR ARTICLE.

Application filed October 31, 1927. Serial No. 23,950. Term of patent 3½ years.

To all whom it may concern:

Be it known that I, HENRY J. RUPP, a citizen of the United States, and resident of the city of Quincy, in the county of Adams and State of Illinois, have invented a new, original, and ornamental Design for a Stove Casing or Similar Article, of which the following is the specification, reference being had to the accompanying drawing, forming a part thereof.

On the drawings:

The figure represents a perspective view of the stove casing, showing my new design.

I claim:

The ornamental design for a stove casing or similar article as shown.

HENRY J. RUPP.
